DISPENSER FOR DENTAL FLOSS AND OTHER FILAMENTS

Charles Castelli, New Brunswick, Arthur R. Meares, Westfield, and Irvin J. Gershen, Springfield, N.J., assignors to Johnson & Johnson, a corporation of New Jersey

Application May 22, 1956, Serial No. 586,590

6 Claims. (Cl. 225—51)

This invention relates to dispensers for dental floss, 15 thread, and other filament.

More particularly, the invention relates to dispensers of the type in which a spool of floss or the like is enclosed in a casing provided with a cutter for cutting off the desired lengths of floss.

The general object is to provide an efficient, inexpensive dispenser adapted to manufacture from plastic such as polystyrene, or other rapid molding cycle inexpensive thermoplastic.

In the dispenser of the invention, a metal floss or filament guide and cutting element is combined with plastic casing elements in such a way that the forces exerted on the parts in normal use tend to hold the assembly together, and in this way close fitting or interlocking between plastic parts and the casting of the metal part as an insert may be eliminated. In consequence, a very simple, compact and reliable dispenser may be made at comparatively low cost.

A floss dispenser embodying the invention in a preferred form will now be described with reference to the accompanying drawing, and the features forming the invention will then be pointed out in the appended claims.

In the drawing:

Fig. 1 is an isometric view of the floss dispenser;

Fig. 2 is an enlarged section on a central of axial 40 plane 2—2 of Fig. 1;

Fig. 3 is an exploded view showing the various parts in side elevation;

Figs. 4 and 5 are, respectively, inside plan views of the cover and body elements of the casing;

Fig. 6 is a top plan view of the metal cutter and guide element of Fig. 2;

Fig. 7 is an isometric view of a modified dispenser;

Fig. 8 is an enlarged side elevation of the cap element of the casing of Fig. 7, part of the bottom element being shown in section;

Fig. 9 is a bottom elevation of the cap of Fig. 8;

Fig. 10 is a central axial section on the line 10—10 of Fig. 7;

Fig. 11 is a front elevation of the cutting element 55 of the device of Fig. 7; and

Figs. 12 and 13 are, respectively, bottom and top plan views of this element.

The floss dispenser comprises a bottom or body casing member 10 fitted with a cover 11 and metal cutter element 12, a package of floss 13 being enclosed by these elements and the end 14 being pulled out and cut off in the manner indicated and later described in detail.

The body or bottom casing element 10 is shown in detail in Figs. 2 3 and 5. It is provided with a pin 15 for locating the lower end of the floss spool, a notch or opening 16 to permit passage of the floss and with recesses 17 adjacent its upper edge for holding the cover 10 in place. The cover 10 which is shown in detail in Figs. 3 and 4, has a shoulder 18 which seats on the top of the bottom 10 and a flange portion 19 which extends

5

10

below the shoulder and fits snugly within the bottom. An opening 20 accommodates the metal cutter fitting 12 and ribs or projections 21 are snap fitted into the recesses 17 for holding the two parts of the casing together. The floss or thread package 13 may be of various forms without departing from the invention in its broader aspect, but conveniently takes the form of a flangeless tube 22 on which the floss 23 is wound, the pin 15 fitting in the lower end of the tube 22, and the tube extending sufficiently close to the top of the cover so as to prevent its coming off the pin.

The metal cutter fitting 12 which is shown in detail in Figs. 1, 2, 3 and 6, comprises a central table portion 25 which fits in and fills the cover opening 20, being approximately flush with the outer surface of the cover member 11. This central table portion 25 is surrounded by side flanges 26 which fit under and against the inner surface of the cover 11 surrounding the opening 20, a lower flange 27 which has a notch 28 registering with the notch 16 previously referred to and which fits inside and against the inner surface of the bottom 10 of the casing. A projecting tongue 29 at the upper end of the fitting 12 fits into a groove 30 formed in the cover 11, holding the fitting 12 at this point against both inward and outward movement, and the lower flange portion 27 fits over somewhat recessed portions 31 of the cover 11, so that the fitting 12 is held against inward movement at this point as well as being held against outward movement by the casing bottom 10.

Immediately above the upper edge of the bottom 10, the metal fitting 12 is formed with a rib or shoulder 32 which preferably engages the upper edge of the bottom 10 and above this ridge the fitting 12 is formed with a depression 33 across which the floss passes on its way to the cutter proper which consists of a tongue 34 partially punched out of the element 10 and having sharp edges against which the floss may be severed. It will be noted that the bottom 10 is considerably longer than the top 11 and that the top 11 is curved or tapered inwardly having a roughly frusto-conical configuration, so that the natural and convenient way to grasp the floss dispenser is as indicated in phantom in Fig. 1, the thumb and finger grasping principally the bottom 10 instead of the top 11. In use, the required length of floss is pulled out, the floss is wrapped around the cutting tongue 34, as indicated in Fig. 1, and a pull on the floss then severs it against an edge of this tongue (the right hand edge in Fig. 1), the end of the unused floss remaining in place and being gripped by the other edge (the left hand edge in Fig. 1) of the tongue 34. Depression 33 permits ready grasping of the end of the floss over the depression 33 for disengaging the floss from the cutter 34, pulling out a required length and severing the same. It is possible to join the element 12 to the cover 11 adhesively, the adhesive being applied in any convenient locations such as over the flange portions 31, but no particular strength of joint between member 12 and the cover is required for the efficient functioning of the dispenser.

It will be noted that in tugging on the floss end to sever the same, a pull is exerted downwardly toward the bottom 10 on the member 12, tending to seat the ridge 32 more firmly against the edge of the bottom 10 and not tending to cause separation of any of the parts from each other. In point of fact, the device works entirely satisfactorily with a loose piece 12, the adhesive joining the piece 12 to the cover 11 being desirable only for preventing detachment and loss of the part 12 when the cover is removed from the bottom for refilling with a new spool of floss. Pin 15 is preferably set back off center as indicated, so that when in unwinding the floss the spool is pulled over toward one side of the unit (to the

left in Fig. 2) so as to take up clearance, the bottom of the spool will occupy a substantially central position.

In the modification of Figs. 7-13, the parts involved and their cooperation with each other are generally similar to the corresponding parts of Figs. 1-6 and are, in general, identified by the same reference numerals with the addition of a suffix letter "a." The description of these parts will not be repeated except to the extent necessary for explaining the modified features.

The casing is formed as before in two parts 10a and 11a, but an improved interlock or joint between these elements is provided. The casing cap element 11a has a depending flange extension 19a, as before, with projections or ribs 21a for interlocking with the bottom. However, the corners of this projection or flange are enlarged outwardly as at 40, and made somewhat deeper at this point. The walls of the lower casing element 10a may be slightly convex, as indicated in Fig. 7, and the parts are dimensioned so that the corner enlargements at 40 when pushed within the bottom 10a will spread the upper part of the casing bottom 10a slightly, straightening out the side walls and bringing them inwardly toward the projections 21a, so that the recesses 17a are forced against projections 21a, engaging and holding the parts firmly together. Adjacent the opening 20a which takes the cutter fitting 12a, the flange 19a is formed with recessed areas 41, for a purpose later described.

The cutter fitting 12a is generally similar to the fitting 12 previously described, except in the particulars now to be pointed out. In the first place, the tongue 34a has a second or subsidiary tongue 42 struck back on its central part as indicated. The tip of this tongue extends to or slightly beyond the plane of the table portion 25a generally, so that the floors end 14a when wrapped around in back of tongue 34a will be in front or outside of the subsidiary tongue 42 instead of catching in back of this subsidiary tongue. Toward the base of tongue 42 it diverges at an angle from tongue 34a, as can be seen from Fig. 10, so that the floss end 14a when pulled downwardly is wedged into the angular opening defined by elements 34a and 42 and is rather securely gripped. This gripping assists in preventing slipping of the floss when pulled so as to cut it against an end of the cutter tongue 34a, and also serves to hold the remaining floss securely in position until the dispensing of another length as desired. In this way, loss of the floss end due to its slipping back through the opening defined by notches 16a and 28a is prevented. The dispenser can be made so economically that the empty casing may be discarded instead of being refilled, and since the loss of the floss end is effectively prevented, it will ordinarily be unnecessary to spread the casing top and bottom once snapped together. At the bottom, the flange 27a is modified by cutting off its lower corners, leaving two laterally projecting ears 43 which fit over and against the recessed areas 41 previously mentioned. These ears are bent inwardly at their lower edges 44, as indicated, and will bite into the plastic material of the casing top 11a to a sufficient extent so as to hold the parts firmly together.

What is claimed is:

1. A dental floss or similar filament dispenser comprising a casing having bottom and top elements forming an enclosure for holding a filament spool, the top element having a depending flange fitting inside the bottom element and the shoulder above the flange abutting against the upper edge of the bottom element, a metal cutter fitting having an upwardly extending upset tongue around which the filament may be wrapped and severed, the casing top element having an aperture interrupting the flange and extending above the shoulder, the said aperture slidably receiving the fitting and the fitting having flange elements fitting within the casing top element above the shoulder and outside the flange for holding it against movement inwardly and outwardly thereof, and the fitting having also a shoulder seating against the upper edge of the bottom part of the casing so as to sustain force exerted upon the fitting by wrapping filament around the said tongue and pulling downward on the same.

2. A dental floss or similar filament dispenser according to claim 1, in which the said depending flange has recesses to each side of the aperture and flange elements on the said metal cutter fitting within the said recesses and inside the bottom element of the casing.

3. A dental floss or similar filament dispenser according to claim 2, in which the flange elements fitting in the said recesses are bent inwardly at their lower edges, and bite into the material of the depending flange for holding the metal cutter fitting in position.

4. A dental floss or similar filament dispenser according to claim 1, comprising also projections formed on the two sides of the said depending flange adjacent to the side edges interrupted by the said aperture and corresponding recesses formed in the bottom element, the said projections and recesses snap fitting together when the casing top and bottom elements are assembled.

5. A dental floss or similar filament dispenser according to claim 4, in which the upper edges of the walls of the bottom element of the casing are slightly convex, and the said depending flange has outward enlargements at its corner for tensioning and spreading the upper edge of the bottom element when inserted therein.

6. A dental floss or similar filament dispenser according to claim 1, in which the said metal fitting has a downwardly opening notch positioned below the edge of the bottom element wall and the bottom element wall has an upwardly opening notch registering therewith, the two said notches forming an aperture for emergence of the filament from the casing.
